2 Claims

ABSTRACT OF THE DISCLOSURE

Apparatus using a single selectively operated valve for flushing a toilet bowl or exhausting odors therefrom and including a reservoir having a supply of liquid under pressure for flushing or venting the bowl.

BACKGROUND OF THE INVENTION**(1) Field of the invention**

This invention relates generally to sanitation within buildings and relates particularly to toilet bowls and the flushing and venting thereof to dispose of waste matter and associated odors.

(2) Description of the prior art

Heretofore many devices for flushing toilets have been provided; however, most of these prior devices have depended upon the opening of a valve which would permit a predetermined quantity of water to flow by gravity into the bowl to flush the contents of the bowl into a drain sewer. Some efforts have been made to vent odors; however, these prior devices have been unsatisfactory since they were expensive and complicated to manufacture and maintain and were subject to design weaknesses which permitted leakage and which have not found general acceptance in the trade.

SUMMARY OF THE INVENTION

The present invention is a toilet flushing and venting mechanism having an operating valve with a handle which can be selectively operated so that in one position water under pressure will be forced into the tank to perform the flushing operation, and in another position water will be forced through a venturi to create a negative pressure within the area of the bowl and exhaust the odors to a sewer. At least one of the liquid lines is provided with a vacuum break to introduce air under atmospheric pressure into the water pressure line in the event of a break in the same which could create a partial vacuum or negative pressure within the toilet and suck material from the sewer line if the negative pressure were not broken. Also an auxiliary reservoir is provided which will be completely or partially filled during the power flush cycle and which will supply liquid to the bowl after the power flush has been completed and the siphon effect of the toilet has drained most of the liquid therefrom.

It is an object of the invention to provide a toilet flushing and venting mechanism including a pressurized tank or reservoir which automatically interrupts the inflow of water into the tank and a single manually operated valve which is selectively operated to introduce liquid under pressure into the toilet bowl for flushing purposes or for directing the liquid under pressure through a venturi for venting odors from the bowl.

Another object of the invention is to provide apparatus for flushing and venting a toilet by using liquid under pressure and providing an auxiliary tank for supplying a predetermined amount of liquid to the bowl after the power flush and siphon have taken place.

2

BRIEF DESCRIPTION OF THE DRAWING

FIG. 1 is a section of a toilet bowl illustrating one application of the invention.

5 FIG. 2 is an enlarged fragmentary section on the line 2-2 of FIG. 1.

FIG. 3 is an enlarged fragmentary section of the connection between the toilet bowl and the power flush line.

FIG. 4 is a section on the line 4-4 of FIG. 3.

10 DESCRIPTION OF THE PREFERRED EMBODIMENT

With continued reference to the drawing a sealed tank or reservoir 10 is provided having an inlet line 11 and a discharge line 12. The tank 10 can be located in any desired position, such as being inset within a wall, or if desired can be placed above and to the rear of a toilet bowl 13. The tank 10 preferably is sealed so that the contents can be maintained under pressure for a purpose which will be described later.

The discharge line 12 terminates in a T-coupling 15 with a three-way valve 16 mounted therein and having an operating handle 17. To one side of the T-coupling 15 a flush line 18 is connected and such flush line projects downwardly into the rear portion of a channel 19 extending substantially entirely around the upper portion of the bowl 13. Around the lower portion of the channel 19 a plurality of spaced openings 20 are provided so that water which enters the channel from flush line 18 will be discharged through such openings into the lower portion of the bowl 13. At the lower portion of the bowl 13 a discharge passage 21 is provided which extends upwardly and rearwardly from an entrance opening 22 to a drain passage 23 connected to a conventional sewer line (not shown). Normally a predetermined amount of water 24 is maintained within the bowl 13 and at a level substantially above the entrance opening 22 so that offensive sewer odors and gases cannot be discharged from the 40 sewer through the bowl.

At the top of the bowl 13 a hollow enlargement 26 is provided through which the flush line 18 extends. The enlargement 26 has a plurality of openings 27 so that air under atmospheric pressure can enter the area between the inner periphery of the enlargement and the flush line 18. In the event of a negative pressure being created in the inlet line 11 ambient air will pass through the openings 27 and into the flush line 18 to interrupt or break the negative pressure. If desired, the flush line 50 18 may have an internal ring 28 with a sharp-edged orifice 29 functioning as a venturi to accelerate the passage of water through the lower portion of the flush line. Such passage will create a partial vacuum in the rear portion of the channel 19 and will draw air under 55 atmospheric pressure through the openings 27 and entrain such air in the water being discharged through the openings 20 of the channel.

An auxiliary tank 30 is disposed about the flush line 18 and is in communication with the interior thereof through upper and lower openings 31 and 32, respectively. When water is passing through the flush line 18 under pressure, some of such water will be diverted through the openings 31 and 32 into the auxiliary tank 30. This is particularly true when the internal ring 28 60 is located below the auxiliary tank since such internal ring will create a slight back pressure which will force the water into the auxiliary tank. After the flow of water under pressure has been halted by operation of the valve 16, the water within the auxiliary tank 30 will drain through the lower openings 32 and be discharged into the toilet bowl to furnish the supply of water 24 which 65 normally is contained within the bowl.

At the other side of the T-coupling 15, an upper vent line 35 is connected to the valve 16 and extends downwardly to a T-connection 36. A lower vent line 37 extends downwardly from the T-connection 36 through a trap 38 and terminates at a connection 39 in communication with the drain passage 23. An air line 40 extends laterally from the T-connection 36 and provides communication with the channel 19. A venturi 41 is located within the upper portion of the T-connection 36 adjacent to the discharge end of the upper vent line 35 and such venturi has a reduced discharge orifice at its lower end. The water passing through the discharge orifice of the venturi is accelerated a substantial amount and is projected past the line 40 into the lower vent line 37. The passage of the water past the line 40 creates a negative pressure or partial vacuum within such line and the channel 19 and draws air from the bowl through the openings 20. Odors within the bowl thus are removed and are discharged into drain passage 23 and sewer.

The water in the inlet line 11 normally is under a pressure of approximately 40 to 60 p.s.i. when it is introduced into the tank or reservoir 10. When the valve 16 is open, water will be discharged through the discharge line 12 at substantially the same pressure that it enters the tank through the inlet line 11. When the valve is closed, water continues to fill the tank so that air trapped within the tank is compressed by the rising water level until the pressure of the air substantially equals the pressure of the water within the inlet line and thereby interrupts the flow of water through such inlet line. When the valve 16 again is opened, the compressive force of the air forces water through the discharge line 12 and simultaneously permits additional water under pressure to enter the tank 10 through the inlet line 11. In this manner the water used in the flush and the vent operation is under pressure at all times; however, the water which fills the auxiliary tank 30 drains by gravity into the bowl after the valve has been closed.

In the operation of the device a predetermined amount of water is retained within a tank or reservoir 10 under pressure. When the toilet bowl is in use the handle 17 of the valve 16 may be turned in one direction to permit water to flow through the vent lines 35 and 37 into the drain passage 23. When water under pressure flows through such vent lines a partial vacuum or negative pressure is created which draws air from the channel 19 and entrains such air into the water being evacuated through the drain passage. The air being drawn through the vent lines will carry with it any offensive odors and will discharge such odors into the sewer. When the handle 17 is operated in the other direction, water under pressure passes through the flush line 18 and the channel 19, and is discharged through the openings 20 into the bowl. When the water level within the bowl rises, such water likewise will rise in the drain passage 23 to create a siphon effect to discharge substantially all of the fluid and semi-solid matter from the toilet bowl into the drain passage 23 and subsequently to a sewer. While water is passing through the flush line 18, some of such water will be diverted through the upper and lower openings 31 and 32 of the auxiliary tank 30 to substantially fill the same. When the valve again is closed and the water under pres-

sure is cut off, the water within the auxiliary tank 30 will drain through the lower openings 32 into the channel 19 and then into the bowl 13.

I claim:

1. A toilet flushing and venting mechanism for use with a toilet bowl having an inlet channel and a drain passage to a sewer, said mechanism comprising a reservoir containing water under pressure, valve means connected to said reservoir, said toilet bowl having a hollow enlargement with at least one opening providing communication between the interior and exterior thereof, a flush line connected at one end to one side of said valve means, the opposite end of said flush line extending through said enlargement and terminating within said inlet channel and adapted to introduce water under pressure thereto, an auxiliary tank disposed about said flush line intermediate the ends thereof, said flush line having upper and lower openings providing communication with said auxiliary tank, a restriction in said flush line below said auxiliary tank for causing water to enter said auxiliary tank when water under pressure is flowing through said flush line, a vent line connected at one end to the other side of said valve means and connected at the opposite end to the drain passage of said bowl, a venturi located within said vent line, an air line connecting the channel of said bowl with said vent line closely adjacent to the downstream side of said venturi, and handle means for selectively operating said valve means so that movement of the handle means in one direction will cause water under pressure to move through said flush line into said bowl to flush the contents of the bowl into the drain passage, and movement of the handle means in the other direction will cause water under pressure to pass through said venturi to draw foul air from said bowl and discharge the same into said drain passage.

2. The structure of claim 1 including an inlet line for introducing water under pressure into said reservoir so that air trapped in said reservoir will be compressed by water entering the reservoir when the valve means is closed and the compressed air will interrupt the inflow of water.
